MUFFLER

Lucien L. Haas, Buffalo, and Gail C. Starkweather, Kenmore, N. Y., assignors to Buffalo Pressed Steel Company, Buffalo, N. Y., a corporation of New York

Application October 7, 1930. Serial No. 486,937

7 Claims. (Cl. 137—160)

This invention relates to improvements in mufflers of the kind commonly employed in connection with internal combustion engines for reducing the noises caused by the exhaust of the engines.

The objects of this invention are to provide a muffler of improved and simplified construction, in which a straight, uninterrupted passage through the muffler is provided, and in which baffles or deflectors are provided which cause portions of the gases to impinge upon other portions of the gases to reduce the noises of the exhaust; also to provide a muffler in which baffles are employed, which are arranged to operate by an ejector action to cause a portion of the gases flowing through one part of a baffle to induce a flow of another portion of the gases through another part of the baffle, and then mixing these two portions of the gases, thus breaking up the sound waves to produce a silencing effect; also to provide baffles of this type with deflectors of improved construction which assist in guiding the two portions of the gases into contact; also to provide a muffler of this kind, in which a baffle may have other parts secured thereto to form a unit, which in turn is secured to the shell of the muffler; also to improve the construction of mufflers in other respects hereinafter specified.

In the accompanying drawing:

Fig. 1 is a central longitudinal section of a muffler embodying this invention;

Fig. 2 is a transverse sectional elevation thereof, on line 2—2, Fig. 1.

In the muffler illustrated in the drawing, and which constitutes one embodiment of our invention, A represents the outer cylindrical shell of the muffler which is provided at one end with a head B suitably secured to the shell and having a short cylindrical projection b, which may be connected with the exhaust pipe of an engine and through which the gases enter the muffler. At the other end of the shell a discharge head C is provided, secured at its outer portion to the shell, and having a tubular projection c, which may be connected to a tail or discharge pipe (not shown), or through which the gases may be discharged directly to the atmosphere. All of these parts, which constitute the housing of the muffler, may be of any suitable or desired construction and of themselves form no part of this invention.

D represents baffles embodying this invention, three of these baffles being shown in the construction illustrated, but it will be obvious that any desired number may be employed in a muffler to produce the desired muffling effect. Each of these baffles is preferably provided with an outer flange 5, which may be welded or otherwise secured to the inner surface of the shell A of the muffler. The baffle is of substantially funnel shape, tapering more or less irregularly in the direction of

the flow of gases through the muffler. The baffle has a substantially central discharge opening or orifice 6 therein, which is preferably in the form of a short tube formed integral with the baffle. The portion of the baffle between the outer flange 5 and the discharge passage 6 may be more or less tapered or stepped toward the direction of flow of the gases, an intermediate inclined portion 7, in the particular construction shown, being provided with a series of apertures or openings 8 therein, through which some of the gases passing through the muffler may flow. By means of this construction, there is a tendency of gases to flow both through the orifice 6 and through the several apertures 8 arranged about this central opening. The flow of gases through the aperture 6 has an ejector action, forming a partial vacuum at the side of the baffle facing the discharge end of the muffler. This action of the gases passing through the central aperture 6 induces a flow of gases through the apertures 8 in addition to the amount of flow that would pass through these openings without the ejector action. The gases passing through these apertures are then mixed with the gases which have passed through the opening 6. This mixing of the gases resulting from the ejector action, together with the impinging of the gases discharged through the openings 8 against the jet of gas from the orifice 6, produces an effective reduction of the noises of the exhaust by breaking up of sound waves.

At the left hand side of Fig. 1, a second baffle E is provided which is similar in construction to the baffle D, except that the baffle E is provided at its outer edge portion with a tubular extension 10 which makes it possible to secure this baffle to a cylindrical portion or shoulder 9 of the baffle D adjacent to the flange 5 but of lesser diameter than the flange 5. This baffle E, acting on the gases in a manner similar to the baffle D and in conjunction with the baffle D, produces a greater silencing effect than the baffle D alone. By means of the construction described, the baffle E can be welded or otherwise secured to the baffle D before the baffle D is secured to the shell A, thus facilitating the assembling of the two baffles in the muffler.

If desired, the ejector action of the baffles may be supplemented by providing means for guiding gases discharged through the openings 8 in the baffles toward the jet of gas discharged through the orifice 6. Any desired construction may be employed for this purpose, that illustrated in the drawing including a deflector F, which may be used in connection with the baffles D or E as shown in Fig. 1. This deflector is substantially bell or funnel shaped, the edges thereof being secured to the shoulder 9 of the baffle D, or if a deflector of this type is to be used in connection with the baffle E, it may, if de-

sired, be secured to a shoulder 11 formed on the baffle E, as illustrated at the left of Fig. 1. The deflector F is provided with a discharge passage or opening 12 which is preferably of somewhat greater diameter than the discharge passage 6 in the baffle D, or of the discharge passage 10a in the baffle E. The concave curved or bell-shaped portion 14 of the deflector is so shaped as to guide any gases discharged through the apertures 8 in the baffle D, or through the corresponding apertures in the baffle E, toward the axis of the muffler. Thus, the deflector F ensures a positive movement of the gases discharged through the apertures 8 toward the axis of the jet of gas discharged through the orifice of the adjacent baffle, and thus causes them to impinge against gases discharged through the passage 6 and also assists in causing a mixing of the gases, thus adding materially to the silencing effect produced by the baffle alone.

In the muffler illustrated, three different arrangements of baffles are illustrated, and mufflers may be built using any one of the three arrangements shown, or using any combinations of these arrangements. The deflectors F have been found very desirable and of great value in helping to silence noises of the exhaust, but it will be understood that it is not necessary to use these deflectors, since satisfactory muffling effects can be produced by merely using baffles alone. Different arrangements of the baffles, and deflectors shown, and any desired number of baffles and deflectors per muffler may also be employed in constructing mufflers for different sizes of engines to produce the desired silencing effect on different volumes of gases discharged by different engines.

By spacing the baffles or baffling units at distances from each other in the shell of the muffler, expansion chambers are formed between the baffles or units in which the gases are permitted to expand. This alternate arrangement of baffles and expansion chambers also assists in silencing noises.

The muffler described is thoroughly effective in operation of sturdy construction, and is also easily manufactured. The baffles and deflectors can be formed by stamping operations and the assembling of the baffles and deflectors into units can be easily done by spot welding or other means, before the units are assembled in a shell, and consequently, the correct positioning of the parts of the units relatively to each other is greatly facilitated. The units or individual baffles, if such are used, can then be very easily secured by welding or otherwise in the single shell of the muffler.

We claim as our invention:

1. A muffler having a housing provided with inlet and discharge openings, a baffle arranged in said housing and having a discharge orifice approximately equal in size to the discharge opening in said housing and openings of smaller size arranged about said orifice, and a deflector arranged within said housing beyond said baffle and having an opening in alignment with said orifice and imperforate walls formed to guide gases flowing through said openings in said baffle toward the jet of gas discharged through the orifice of said baffle.
2. A muffler having a housing provided with inlet and discharge openings, a baffle arranged in said housing and having a discharge orifice approximately equal in size to the discharge opening in said housing and openings of smaller size arranged about said orifice, and a deflector

mounted on said baffle and having a discharge opening larger than said orifice and in alignment therewith and having an imperforate wall for guiding gas discharged from said openings of said baffle toward the jet of gas passing through said orifice.

3. A muffler having a housing provided with inlet and discharge openings, a baffle arranged in said housing and having a discharge orifice approximately equal in size to the discharge opening in said housing and openings of smaller size arranged about said orifice, and a deflector secured on said baffle having a concave portion formed to guide gas discharged from said openings toward the jet of gas discharged through said orifice and having an opening in alignment with said orifice of said baffle, said deflector being otherwise imperforate.

4. A muffler including a substantially cylindrical housing, a substantially funnel-shaped baffle secured to said housing within the same and which tapers in the direction of flow of the gases through said muffler, and which has an orifice in the smaller end thereof and openings arranged about said orifice, and a deflector supported entirely from said baffle and having a curved portion which guides gases discharged through said openings radially toward the jet of gas discharged through said orifice.

5. A muffler having an outer shell and having inlet and discharge openings, a substantially funnel-shaped baffle arranged within said shell and tapering in the direction of flow of gases through said muffler, the outer portion of said baffle being secured to the shell of the muffler, said baffle having a discharge orifice in the smaller end thereof approximately equal to the discharge opening of the muffler, and openings of smaller size arranged about said orifice, and a deflector supported entirely on said baffle and having walls which curve inwardly toward the axis of the orifice of said baffle to guide gases discharged through said openings towards the sides of the jet of gas discharged through said orifice.

6. A muffler having an outer shell, a baffle arranged in said shell and having a flanged peripheral portion secured to said shell, said baffle tapering in the direction of flow of gases through the muffler and being provided with a substantially central discharge orifice, a substantially cylindrical shoulder portion formed on said baffle and of less diameter than said flange, and discharge openings in said baffle arranged between said orifice and said shoulder, and gas deflecting means secured to said shoulder for deflecting gas discharged through said openings toward the jet of gas discharged through said orifice.

7. A muffler having an outer shell, a baffle arranged in said shell and having a flanged peripheral portion secured to said shell, said baffle tapering in the direction of flow of gases through the muffler and being provided with a substantially central discharge orifice, a substantially cylindrical shoulder portion formed on said baffle and of less diameter than said flange, and discharge openings in said baffle arranged between said orifice and said shoulder, and a substantially bell-shaped deflector having a central opening and having its portion of greatest diameter secured to said shoulder for deflecting gases discharged through said openings toward the jet of gas discharged through said orifice.
